[57] CLAIM

The ornamental design for a transfer pipette, substantially as shown.

DESCRIPTION

FIG. 1 is a top plan view of the transfer pipette showing my new design;

FIG. 2 is a side elevational view of the transfer pipette taken from the bottom of FIG. 1, the other side being a mirror image thereof;

FIG. 3 is an end elevational view taken from the left side of FIG. 2;

FIG. 4 is an end elevational view taken from the right side of FIG. 2; and

FIG. 5 is a transverse section along line 5—5 of FIG. 2.
